PORTABLE ASH TRAY FOR FURNITURE

Robert Lee Fischer and Don A. Fischer,
Kirkwood, Mo.

Application January 21, 1952, Serial No. 267,405

6 Claims. (Cl. 155—188)

1

This invention relates to improvements in portable receptacles easily attached to the underside of chairs or tables.

It is an object of this invention to provide an improved drawer which may be attached to the underside of a table or chair without tools or without the use of nails, screws or other permanent fastening means.

It is another object of the invention to provide the improved receptacle or drawer with means for attaching it to the underside of a chair or table without inverting or otherwise disturbing the chair or table.

Another object of the invention is to provide a portable receptacle which may be attached to the underside of a chair or table regardless of the material or construction of the chair or table.

Further objects and advantages of this invention will become apparent from the following detailed description and the accompanying drawings.

In the following description and accompanying drawings, we have shown only one embodiment of the invention. Others will become apparent as the description proceeds.

Referring to the drawings:

Figure 1 is a perspective view of the portable drawer of the invention.

Figure 2 is a perspective view of the drawer attached to the underside of a chair.

In the embodiment shown, the portable receptacle has a support 10 which may enclose the drawer 12 and may be formed of metal, plastic or other suitable material. This support need not entirely enclose the drawer but such enclosure is often desirable when the drawer is to be used as an ash tray. The drawer slides in the support and may be provided with a face 14. This face may have a depending edge 16 serving as a finger pull and as a stop for the drawer. A pair of inwardly turned hooks 18 are attached to the support. These may be soldered to the support if it is metal or fastened in other ways commonly employed. The ends 20 of these hooks are sharpened to points. An elastic strap 22 is secured to the support by passing through slot 24 in the shell. This strap has a buckle 26 provided at its end and an adjusting strap or sliding buckle 27 secured in the usual manner. The buckle 26 is provided with a hook 28 shaped as shown.

A depending tab 30 prevents the drawer from being inadvertently withdrawn from the shell although it will allow removal of the drawer if it is tilted up.

2

To install the drawer beneath a chair, the shell is held so that hooks 18 engage the lower edge of the chair 32. The hook 28 is then positioned to engage the opposite edge of the chair 34. The tension of the elastic pulls the hooks 18 into the upholstery and at the same time maintains the drawer shell in a position substantially parallel to the bottom of the chair. Before installing the receptacle beneath a chair, the elastic strap should be adjusted in length so that suitable tension will be provided when the hook 28 is positioned. If the chair is provided with exposed springs or webbing, the hook 28 may be fastened thereto instead of the opposite edge of the chair as shown. After the receptacle is installed, the drawer may be easily opened and closed by a person sitting on the chair. The device as described has the advantage of being suitable for installation on any chair regardless of the bottom construction and regardless of whether or not the edge is provided with a wood rail. The drawer may be shallow and the front face 14 constructed to blend with the furniture so that it is unobtrusive. It should be noted that no tools are needed for installation, and it is not necessary to tilt the chair or to move it out of normal position.

It is obvious that a spring could be used instead of the elastic strap.

It should also be noted that this receptacle can be attached to any of the thousands of different kinds of chairs or sofas now in use.

The drawer is particularly useful as an ash tray and does away with the usual search for the other type of portable trays.

While we have shown one embodiment of our invention, we do not desire it to be limited thereby but to be defined by the following claims.

We claim:

1. An accessory adapted to be secured to the underside of a piece of furniture comprising a support, a fastening means on the front edge of said support adapted to engage an edge of the furniture, a receptacle movably mounted on said support and adapted for movement from under said furniture to allow access thereto, resilient means secured to the back of said support and a fastening means on said resilient means said last named fastening means adapted to engage the furniture in such a manner that said first named fastening means is held in engagement with said furniture.

2. An accessory adapted to be secured to the underside of a piece of furniture comprising a support, a fastening means on the front of said

support adapted to engage an edge of the furniture, a receptacle movably mounted on said support and adapted for movement from under said furniture to allow access thereto, tension means secured to the back of said support and a fastening means on said tension means said last named fastening means adapted to engage the furniture in such a manner that said first named fastening means is held in engagement with said furniture and the top of said support is held against the underside of said furniture.

3. An accessory adapted to be secured to the underside of an article of furniture comprising a shell, a drawer slidably supported in said shell, inwardly projecting hooks on the front of said shell adapted to engage a part of the article of furniture, a resilient means secured to the rear of said shell and adapted to be secured to the article of furniture to maintain the top of the shell against the underside of said furniture and the drawer in operative position.

4. An accessory adapted to be secured under a chair comprising a shell, inwardly turned hooks on the front of said shell adapted to engage an outer edge of the chair, an elastic band secured 25 at one end to the rear of said shell, a hook on the other end of the elastic band, said last named hook being adapted to engage another part of the chair in substantially the same horizontal plane as the shell to place the elastic band under tension and to maintain the top of the shell against the underside of said chair, and a drawer slidably supported in said shell adapted for movement from under said chair.

5. An accessory adapted to be secured beneath 35 an article of furniture comprising a support, a

drawer slidably supported by said support adapted for movement from under said furniture, anchoring means secured to the front of said support adapted to engage the article of furniture, a tension producing means secured to the back of said support and adapted to be secured to the article of furniture to maintain the drawer and support in operative position.

6. An accessory adapted to be secured beneath a chair comprising a drawer support, a drawer slidably mounted therein adapted for movement from under said chair, hooks on the front of the drawer support adapted to engage the bottom outside edge of a chair, an adjustable resilient means secured at one end to the rear of the drawer support and a hook secured to the other end of the adjustable resilient means, said last named hook being adapted to engage another part of a chair to maintain the drawer support substantially parallel to the bottom of the chair.

ROBERT LEE FISCHER.
